UNITED STATES PATENT OFFICE.

EDWARD BENNIS, OF BOLTON, ENGLAND.

APPARATUS FOR SUPPLYING FUEL TO FURNACES.

SPECIFICATION forming part of Letters Patent No. 691,232, dated January 14, 1902.

Original application filed December 28, 1897, Serial No. 663,865. Divided and this application filed October 29, 1900. Serial No. 34,822. (No model.)

To all whom it may concern:

Be it known that I, EDWARD BENNIS, engineer, a subject of the Queen of Great Britain, residing in Bolton, in the county of Lancaster, 5 England, have invented certain new and useful Improvements in Apparatus for Supplying Fuel to Furnaces, of which the following is a specification.

This invention relates to apparatus for supplying fuel and air to furnaces.

Referring to the accompanying drawings, Figure 1 is a cross-section of the stoker, also showing the fire-bars; Figs. 2 and 3, enlarged views of the mechanism for feeding and distributing the fuel, and Fig. 4 a sectional plan of Fig. 3.

In the drawings, A is a hopper for the fuel, and A' a box, preferably rectangular in shape, the bottom of which is extended at a, so as to form a shelf or table for the feed-plate B to rest on. This feed-plate B is moved to and fro by a bell-crank lever C, Fig. 4, actuated by a scroll-cam D, which cam has an equal number of lifts upon it to 25 those on a cam, to be hereinafter described, which operates a plate which pushes the fuel into the furnace. The scroll-cam D is so constructed that the distance apart of the portions d can be regulated or adjusted by 30 means of a lever E and screw F, thereby regulating the throw of bell-crank lever C and the amount of fuel fed to the furnace by the feed-plate B. In my earlier experiments the fuel when small and dry was apt to run 35 through the box A' and choke the fire and so produce smoke. Now this is entirely obviated by means of a plate G, which is suspended on a pivot in the box and extends downward nearly to the level of the front of 40 the feed-plate B and at the point which such plate reaches when pushed forward, so that when the feed-plate is drawn back a space or recess is left to be filled with fuel and when moved forward pushes such fuel under the 45 suspended plate G and over the end of the shelf a, each successive push causing nearly the same amount of fuel to be pushed over, the exact quantity being regulated by the screw F. This plate G is held in position by 50 a spring H and stop I, so that it can give way slightly, the effect of this arrangement, be-

ing to entirely prevent fuel being fed except when pushed over by the plate B, which is simply a necessity for marine firing, where the motion of the vessel would otherwise cause the fuel to run through of itself.

The fuel which is pushed over the shelf a falls on the bottom K of the box in a heap across and in front of a striker L. This striker L consists of a plate of steel or other 60 suitable material the front of which is V-shaped for the purpose of causing the fuel to be scattered all over the fire, and the top is turned over to form a shield to prevent the fuel getting behind it when it passes beyond 65 the end of the shelf; this shield never entirely leaving the shelf.

The striker is fastened to or forms a part of a striker-arm M, arranged on the outside of the box, and is bent round to avoid the shaft 70 N and also to give springiness and which passes down one or both sides of the box and is bent under to clear. The upper portion of the striker is mounted on a pin or shaft O and has a projection P upon it for the cam Q 75 to bear against, and it is pivoted at R to a piston-rod S to be hereinafter described.

The striker-arm M is operated by the spring-actuated piston-rod S, which works in the cylinder T and has a piston with piston-rings 80 U thereon.

V is a spring pressing against the piston in such a manner as to push the striker L through the action of the striker-arm M toward the fire. This piston is made so as to form 85 a plunger and fill up the closed space at the other end of the cylinder. The tension of the spring V is regulated by the end V' of the cylinder having a thread, so that it can be screwed into the cylinder to any desired 90 extent. If the cam or tappet Q be rotated, the striker-arm M is pushed back, as shown in Fig. 3, carrying the striker L with it, and when released by the cam it bounds forward, as shown in Fig. 2, among the fuel deposited 95 by the pusher-plate B in front of it and scatters the fuel over one zone of the fire.

The cam-wipers have each a different radius, so as to push back the striker to various distances, and so put the spring V into 100 various degrees of tension, so as to throw the fuel to different distances, the closed end of

the cylinder being unaltered and acting as a buffer to take up the unexpanded force.

The cam Q may have either three or four wipers Q'; but in either case at each revolution of the cam all the fire is covered and the action recommences.

The lifts on the scroll-cam D, that actuate the lever C, are made of varying heights to correspond with the extent of the throw, the lesser throw having a less feed, as the front of the fire gets a small amount from each throw, and were the feed always equal would get too much and the fire would not be equally good. The cam D and striker-cam Q are both on the same shaft N, which passes through the boxes and is driven from one end by any suitable gear.

This application is a division of my former application, Serial No. 663,865, filed on or about December 28, 1897.

In Fig. 1 I have illustrated a portion of the apparatus shown, described, and claimed in the application aforesaid for the purpose of clearly illustrating the relation of the present invention to furnace structures. In said figure, *b* designates the main furnace-bar carrying a series of smaller interlocking grid-bars *c*. The main bar *b* is provided with a downwardly-projecting arm or striker *l*, which is acted upon by a cam *j* to move it rearwardly, the cam likewise acting upon the member *i*, extending down from the bar, to draw the bar forwardly. A cross member or support *n* is provided for the forward end of the bar, and a dead-plate *p* fits over the forward end of the bar or bars.

I claim as my invention—

1. In an apparatus for feeding fuel to a furnace, the combination of a hopper; a feed-box located below said hopper and in communication therewith; a shelf *a* located within said feed-box; a feed-plate working on said shelf; a plate pivotally mounted in the upper portion of said box and extending down toward the feed-plate; a spring for normally holding said plate in a vertical position and permitting it to be moved forward by a charge of material; and a striker working in the lower portion of the feed-box beneath the shelf, substantially as and for the purpose described.

2. In an apparatus for feeding fuel to a furnace, the combination of a hopper; a feed-box located below the same and in communication therewith; a shelf *a* extending forwardly in said box; a feed-plate working on said shelf; a plate *G* pivotally mounted in the upper end of said box and extending downwardly toward the shelf; a spring connected to said plate and normally drawing the lower end of the same back toward the hopper; a stop to limit said rearward movement; and a striker mounted in the lower portion of the box, said striker serving to discharge and dis-

tribute the charge of material which passes to the lower portion of the box from off the shelf, substantially as and for the purpose described.

3. In an apparatus for supplying fuel to a furnace, the combination of a hopper; a feed-box located below the same and in communication therewith; a shelf *a* mounted within the feed-box; a feed-plate mounted on said shelf; a plate *G* pivotally mounted in the upper portion of the box and extending down toward the feed-plate; a spring connected to said plate and normally holding the same in a substantially vertical position; a striker working in the lower portion of the feed-box; an arm for supporting said striker, said arm being pivotally supported at a point in the upper portion of the feed-box; a cam working in connection with said striker-supporting arm and serving to force the same back; a cylinder pivotally mounted in rear of said striker-arm; a piston mounted within said cylinder and having its rod extended forwardly and pivotally connected to the striker-arm; and a spring *V* mounted within the cylinder intermediate the piston and the rear end of the cylinder.

4. In an apparatus for feeding fuel to a furnace, the combination of a hopper; a feed-box located below the same and in communication therewith; a shelf mounted within said feed-box; a feed-plate mounted on said shelf; a bell-crank lever *C* having one arm in operative relation with the feed-plate; a rotatable and adjustable cam *D* in operative connection with the outer end of the bell-crank lever; a lever *E* connected to said cam; means for shifting said lever and thereby shifting the cam; a plate *G* pivotally mounted in the upper portion of the box and extending down toward the feed-plate; a spring connected to said plate and normally holding the same in a substantially vertical position; a striker working in the lower portion of the feed-box below the shelf; an arm for supporting said striker, said arm being pivotally supported at a point adjacent to the upper portion of the feed-box; a cam working in conjunction with said striker-supporting arm and serving to force the same back; a cylinder pivotally mounted in rear of said striker-arm; a piston mounted within said cylinder and having its rod extended forwardly and pivotally connected to the striker-arm; and a spring *V* mounted within the cylinder intermediate the piston and the rear end of the cylinder.

In witness whereof I have hereunto signed my name, this 18th day of October, 1900, in the presence of two subscribing witnesses.

EDWARD BENNIS.
